UNITED STATES PATENT OFFICE

WILLIAM A. SCHOENING, OF CHICAGO, ILLINOIS

WINDOW CONSTRUCTION

Application filed July 2, 1931. Serial No. 548,344.

This invention relates to improvements in window construction of the class in which the window sashes are pivoted to slideable runners in the window frame, so that the window sashes are not only vertically movable, but are also capable of being swung inwardly about their lower ends as a pivot.

The main objects of the invention are to provide improved means for facilitating the swinging movements of the sashes and for retaining the sashes at any desired position in their arc of movement, and also to provide improved means for locking or releasing the sashes at any desired position in their vertical sliding movement whether the sashes are opened or closed. A further object is to provide positive locking means for preventing further opening movement of the sashes when swung open to ventilating position.

Other improvements and advantages will become apparent from the following detailed description of one preferred construction embodying the invention, it being understood that changes in the illustrative details of construction here disclosed are capable of being made without departure from the scope of the invention as defined in the appended claims.

In the accompanying drawings:

Figure 1 is a view in elevation of a window structure embodying the invention as seen from the inside of a room;

Figure 2 is a vertical section, in an enlarged scale, as viewed on the line 2—2 (Figure 1), the ventilating positions of the sashes being shown in dotted lines;

Figure 3 is also a vertical section on the line 3—3 of Figure 1, showing the sashes in reversed position and the upper sash swung in as for washing;

Figure 4 is an enlarged detail view of one runner and its sash supporting check arm;

Figure 5 is a detail view of the slide block forming part of the runner shown in Figure 3, as viewed in vertical section, enlarged scale, on the line 5—5 of Figure 4;

Figure 6 is an enlarged detail view on line 6—6, Figure 5, of the ratchet band forming part of each runner;

Figure 7 is a horizontal sectional detail

view on the line 7—7, Figure 1, showing the sash locking device; and,

Figure 8 is a detail of the operating means for the sash locking means.

Referring to the particular embodiment of the invention here illustrated, 10 indicates the window frame or casing having the usual vided with an insert 13 to permit the lower sashes 11 and 12. In the present instance, the upper end of the casing, or lintel, is provided with an insert 13 to premit the lower sash to be raised above the upper sash enough to allow the upper sash to be lowered below the lower sash, when that has been raised, and then swung to washing position, as illustrated in Figure 3.

The slide grooves for the sashes are in fact slide grooves for two pairs of runners generally designated as 14 and 15, to which the respective sashes are pivoted at the bottom, as at 16 and 17, so that they may be swung vertically inwardly.

The pivot 17 of the lower sash is preferably offset inwardly to permit the sash to clear the sill piece when being swung to ventilating position with the sash down and the runners locked, as illustrated by Figure 2. Notches or slots are provided at the ends of the sill piece to receive the lugs of the offset pivot when the sash is down. The runners may be constructed of a wood base or body 18 (Figures 5, 6 and 7), shaped to fit the slide grooves of the window casing, and a metal strip or facing 19 suitably secured to the wood base and preferably rebent or hooked, as at 20 (Figure 7), to enter a vertical groove 21 on the outer side of each sash and make a weather proof joint when the sash is swung to closed position. The upper end of each runner is longitudinally channeled at the rear to receive the weight tape or cord 22 (Figure 5) of the usual counter-balance weight, the end of which is anchored to a screw 23 at the lower end of the channeled portion.

The middle and lower portions of the wood base or body of each runner are channeled on the outer face to a point short of its lower end and this channel is covered by a metal facing strip 19 which is provided with a

vertical slot 24 opening into the channel but not extending as far down the runner. In effect, therefore, each runner is formed with a hollow or tubular portion, into the upper portion of which the slot 24 opens. For a distance substantially coextensive with the slot 24, the back wall of the channel or hollow in the runner is covered by a metal ratchet band 25 formed with a series of rounded depressions or seats 26 (Figures 5 and 6). The channel has in it a slide block 27 having a screw stud 28 which projects through the slot 24 and forms a pivot for one end of a check arm or bar 29, the other end of which is pivoted to the sash. The block 27 is also provided with a spring pressed catch adapted to cooperate with the notches or seats in the ratchet band 25, and this may consist of a plunger, such as a ball 30, seated in a bore or hole in the block and impelled by a compression spring 31. The arrangement is such that movement of the two blocks as a sash is swung down to open position or up to closed position will cause the balls or plungers 30 to successively engage the seats 26 and tend to yieldably hold the blocks and, therefore, the sash, in any desired position. For cooperation with this sash holding means when desirable, as when heavy sashes are to be used, the lower end of the channel in the runner contains a coil spring 32 (Figure 4), which is preferably of such length as to leave some free space between its upper end and the lower side of the block 27 when the sash is closed and the block is in its uppermost position, as in Figures 4 and 5. This will allow initial opening movement of the sash to be made freely, but, as the sash swings downwardly and the weight to be supported by the operator of the sash increases, the block will contact with and compress the spring 32 more and more, thus effectively neutralizing a sufficient amount of the weight of the sash to make upward swinging movement comparatively easy. At the same time, the resistance to movement afforded by the ratchet is so gauged as to neutralize the thrust of the spring 32 and permit the sash to remain in any desired open position.

In connection with means for locking the sashes against sliding movement when the window is closed and also when the sashes have been moved vertically to open the window any desired distance at the top or bottom, the runners 14 are provided with a suitable number of vertically spaced notches in their exterior surfaces. For purposes of illustration, the upper runners 14 are shown as having notches 33 (Figure 2) in their lower ends, while the lower runners 15 are shown with similar notches 34 at their upper ends. When the window is closed, these notches are in the same horizontal plane. The upper runners may also be provided with similar notches 33^a and 33^b for a pur-

pose to be described. The lower runners may also be provided with additional notches at desired points in their lengths, as at 34^a. For cooperation with the several notches the window casing has mounted in it at each side, in the same horizontal plane as that in which the notches 33 and 34 lie when the window is closed, with a pair of spring pressed latch pieces or plungers 35 and 36 (Figure 7) housed in boxes or holders 37 and 38 set in the material of the window jamb or casing. The two plungers at each side are controlled simultaneously by means of polygonal rods or shafts 39 extending to the inner face, or room side, of the window casing where they terminate as manually operable elements such as the angular hand pieces 40.

The inner end of each rod 37 is slidably journaled in suitable bearings on the members 37 and 38 and is operatively connected to the plungers 35 and 36, so that a quarter oscillation of the rod in a clockwise direction will withdraw the plungers against the action of their impelling springs, in the well known manner used in connection with ordinary door latches. The outer end of each rod passes through a suitable rosette or bearing socket 41 secured to the surface of the window casing and formed with an annular flange 42 within which an enlarged cylindrical portion on the hand piece or end of the shaft may turn. The rod 39 is pressed axially outwardly by a spring 43 surrounding the rod and held between a collar 44 on the rod and an annular flange 45 on the end of a thimble 46 set in the material of the casing and surrounding the rod 37. The socket 41 is formed with opposite notches 47 on its inner side (Figure 8) and the enlarged end of the rod has opposite lugs 48, against which the collar 44 bears and which are adapted to seat in the notches and be held there by the thrust of spring 43.

With the sash locking mechanism just described, the plungers 35 and 36 will seat in the notches 33 and 34 when the sashes are respectively raised and lowered to close the window, as in Figure 2. As the upper sash is then seated behind a depending guard 49 at its upper edge, it can neither be swung nor moved vertically, while the lower sash is correspondingly locked by the plunger seated in the notch 34 at its upper end. Referring to Figure 8, a quarter turn given the hand pieces 40 to dotted line position will cause lugs 48 to seat in notches 47 and lock the rods 39 with the plungers 35 and 36 withdrawn from possible engagement with any of their complementary notches in the sashes, and the sashes are then free to slide. A slight push and reverse turn to full line position causes the lugs 48 to leave the notches and ride on the edge of the opening in socket 41, and the sashes are locked. The sashes may, of course, be locked in partly raised and

lowered positions by provision of such notches as 33^a in the upper sash and 34^a in the lower sash. In the present instance the notch 33^a is shown as positioned a sufficient distance above notch 33 to permit the upper sash to be lowered and locked in position to clear the guard 49, when it can be swung to ventilating position and into engagement with stops 50, as shown in dotted lines in Figure 2. This sash is thus locked against sliding and further tilting movement.

To permit similar tilting of the lower sash to ventilating positions, the sides of the window casing may be provided with an arcuate series of seats or notches 51 cooperating with thumb latches 52 on the sash, thus providing for variable tilting adjustment thereof and securely locking the sash in position. Ordinary thumb latches 53 may be provided on the upper sash to prevent tilting when that sash is partly lowered.

The runners 14 and 15 project only slightly beyond the side panels of the window frame, as best shown in Figure 7, and the lower sash can be tilted on its offset pivot 17 without raising it. Therefore, the sashes can be partly opened by tilting to ventilating positions, as indicated by the broken lines, Figure 2, without admitting rain or objectionable horizontal air currents or drafts, as the longitudinal edges of the sashes will lie close to the side panels of the frame and, as the lower sash tilts on the inwardly offset axis of pivots 17, there is no opening produced at the lower edge of the lower sash. This feature constitutes an important advantage of my window construction.

For ready access to the respective sashes from the inside of a room, as for washing or repair, the upper sash can be lowered and swung to the position of Figure 3. At the same time, the lower sash can be brought down from the extreme upper position shown in said figure sufficiently to clear the stops 50 when it can also be swung inwardly in parallel relation to the upper sash.

It will accordingly be evident that a window structure has been provided embodying novel features giving it a wide range of movements and adjustments and permitting the sashes to be readily set in various open positions and securely locked, and also one in which the handling of the sashes during swinging movement is made easy by resilient devices for sustaining the weight of the sashes.

What is claimed is:

1. A window construction comprising the combination with a window frame having vertical side grooves, of runners slidable in said grooves, a window sash pivoted to said runners to swing vertically into open or closed positions, means for assisting swinging movement of the sash to closed position, and means interposed between the sash and

runners for holding the sash in various open positions against the action of said assisting means.

2. A window construction comprising the combination with a window frame having vertical side grooves, of runners slidable in said grooves, said runners having a portion formed with a longitudinal channel having ratchet depressions in one side, a window sash pivoted to said runners below the channels to be swung downwardly into open position or upwardly into closed position, a block slidably mounted in each channel, a spring pressed plunger carried by each block and cooperating with said ratchet depressions, and check bars pivoted to the respective blocks and to the sash.

3. A window construction comprising the combination with a window frame having side panels and vertical side grooves, of two pairs of runners slidable in said grooves, upper and lower sashes pivoted to the respective pairs of runners to be swung vertically into open or closed positions between said panels, means on the side panels for engagement by each sash to fix them in partially open or ventilating positions, and means mounted in opposite sides of the window frame and engageable with the respective runners for each sash for locking said runners against sliding movement.

4. A window construction comprising the combination with a window frame having a plurality of vertical side grooves, of upper and lower sashes having side pieces slidable in said grooves, said side pieces being provided with vertically spaced notches, spring pressed plungers in the window frame engageable with said notches in the respective sashes, and a single control element connected to the plungers for both sashes and operable to withdraw the plungers from the notches, said control element having an actuating portion projecting from the window frame.

5. A window construction comprising the combination with a window frame having vertical side grooves, of a window sash having its side pieces slidable in said grooves, said side pieces being provided with vertically spaced notches, a spring pressed plunger in each side of the window frame engageable with said notches, a shaft journaled in the window frame at each side of the window perpendicularly to the sash and connected to the respective plungers so that oscillation of the shafts withdraws the plungers, and a hand piece on each shaft projecting from the inner sides of the window frame.

6. A window construction comprising the combination with a window frame having vertical side grooves, of a window sash having its side pieces slidable in said grooves, said side pieces being provided with verti-

- ally spaced notches, a spring pressed plunger in each side of the window frame engageable with said notches, a shaft journaled in the window frame at each side of the window perpendicularly to the sash and connected to the respective plungers so that oscillation of the shafts withdraws the plungers, and means for locking the shaft after a limited degree of angular movement.
7. A double sash window construction comprising a window frame provided with vertical side grooves and inwardly extended side and sill panels; opposite runners slideable in the grooves, a lower sash pivoted on the lower end of the runners by inwardly projecting pivot members having a transverse axis of pivotal movement offset inwardly from the plane of the sash whereby said sash may be swung inwardly when lowered and in engagement with the sill, and interlocking elements on the sash and the side panels for locking the sash in tilted position about said transverse axis and between said panels.
8. A window construction comprising a window frame provided with vertical side grooves and inwardly extended side and sill panels, two pairs of runners slideable in said grooves, upper and lower sashes pivoted to the lower ends of the respective pairs of runners for tilting movement vertically between the side panels, the pivotal connection of the lower sash to the runners being on an axis offset inwardly from the plane of the sash whereby said sash may be swung while in contact with the sill, means on the side panels for holding one or both sashes in tilted positions between said panels in ventilation, and means for locking the respective pairs of runners including lock control means mounted in the window frame.

In testimony whereof I affix my signature.
